GEORGE V. SHEPARD AND WILBUR L. SHEPARD, OF WEST HARTFORD, CONNECTICUT.

CARBURETER.

1,285,812.

Specification of Letters Patent. Patented Nov. 26, 1918.

Application filed October 17, 1916. Serial No. 126,105.

To all whom it may concern:

Be it known that we, GEORGE V. SHEPARD and WILBUR L. SHEPARD, each a citizen of the United States, and a resident of West 5 Hartford, in the county of Hartford and State of Connecticut, have invented a new and Improved Carbureter, of which the following is a specification.

Our invention relates to the class of devices employed in connection with gas engines for mixing the air with the fluid fuel from which the gaseous mixture is produced, and an object of our invention, among others, is to provide a device of this 10 class that shall be particularly efficient in its operation and shall produce mixtures suitable to a wide variety of conditions, and in such manner as to economize the use of fuel.

20 One form of device embodying our invention and in the construction and use of which the objects herein set out, as well as others, may be attained, is illustrated in the accompanying drawings, in which—

25 Figure 1 is a view in central vertical section through a carbureter embodying our invention.

30 Fig. 2 is a view in section through the same on plane denoted by dotted line 2—2 of Fig. 1.

In the accompanying drawings the numeral 5 indicates the shell or bowl of our improved carbureter that may be constructed of any suitable material and of any desired shape, that shown herein being round 35 in cross section. This bowl has an extension 6 containing an inlet recess 7 with which an inlet pipe 8 communicates. A valve 9, herein shown as of the needle type, is mounted

40 for longitudinal reciprocating movement in the extension 6, this valve being supported by a float lever 10 pivotally mounted in the extension and having at the end opposite the valve a float 11 located within the bowl.

45 Fluid passages 12 extend from the lower end of the chamber in the bowl into a chamber 13 from which a passage to a drain cock 14 extends. A cap 15 is secured to the top of the bowl or shell and has an inwardly projecting tube 16 screw threaded into the bottom of the bowl and having a passage communicating with the chamber 13. All of the parts thus far described may be of any well known construction and further and

50 detailed description is, therefore, omitted herein. A valve casing 17 is mounted on

the cap 15 and has a valve chamber 18 therein with a passage 19 extending from said chamber into a carbureting chamber 20 from which a tube or other connection may lead 60 to the engine in which the mixture is to be employed. The passage through the tube 16 communicates with the valve chamber 18, and a valve operating lever 21 is pivotally mounted on the top of the valve casing. 65

A valve 22 is mounted for reciprocating movement in the valve chamber and is operatively connected with the valve lever as by means of interengaging teeth as shown in Fig. 1 of the drawings. Air passages extend through the valve from an air inlet 23 at one end of the valve casing. As shown herein there are two annular chambers 24, one at each end of the valve and they are joined by passages 37 located on opposite 75 sides of a web 25 within the valve and through which a fuel passage 26 extends, communicating with the passage through the tube 16, this fuel passage being enlarged as at 27. The annular chambers 24 are in 80 fact formed by tubular extensions 28—29 projecting in opposite directions from the web 25, the extension 28 having a passage 30 communicating with the passage 26 and preferably of a size somewhat larger than 85 said passage 26. A port 31 extends from the passage 30 out at the end of the valve, flow of fuel through this port being controlled as by a needle valve 32, one end of which is screw threaded into the extension 29. The 90 position of this valve may be changed as by an adjusting piece 33 having one edge notched to correspond with the notched end of the extension 29. This adjusting piece has a recess, preferably of angular form to 95 correspond with the angular shaped head 34 of the valve, and a spring 35 in the recess in the adjusting piece holds said piece with the notches thereon yieldingly engaging the notches in the head of said projection. A 100 slight pull outwardly on the knurled flange of this adjusting piece will disengage said notches and allow the adjusting piece and the valve to be turned to the position desired. Upon the release of force on the adjusting piece the spring will force it inward and cause said notches to reengage and hold the adjusting piece and valve in 105 this position.

This valve is of peculiar advantage in 110 that the fuel and air supplied to the carbureting chamber may be automatically con-

trolled and the relative amounts may be varied to almost any degree. The valve lever 21 will be connected at any suitable point with a manually operated device, and 5 it will be noted that by moving the upper end of the valve lever 21, as seen in Fig. 1, to the left, the valve will be moved to the right and the amount of air flowing to the carbureting chamber will be gradually lessened as the valve approaches its seat 36, 10 and will be shut off when the valve reaches its seat and with the lever in the position shown by the dotted line at the left of the lever in Fig. 1. This movement of the valve 15 will pass the enlargement or mouth 27 of the passage 26 across the passage through the tube 16 and thus gradually shut off the amount of fuel. By moving the valve lever 21 from the closed position above described 20 in the opposite direction the valve will be moved toward the left reversing the conditions as to the supply above described until the valve reaches the point with the valve lever in the position shown in Fig. 1. By 25 continuing this movement of the valve lever toward the right from the point illustrated in Fig. 1, to the point denoted by the dotted line at the right of the lever, the mouth 27 of the fuel passage will be gradually closed 30 while the supply of air into the carbureting chamber will be gradually increased in proportion to the amount of fuel until a point is reached at which the fuel will be entirely 35 shut off and a large amount of air in proportion to the amount of fuel will be admitted.

The engine may, therefore, by the use of this single valve, be supplied with air and fuel, or the same valve may be used to change the proportions between the air and 40 fuel by gradually lessening the amount of fuel and at the same time without decreasing the supply of air which is a result greatly to be desired.

In accordance with the provisions of the 45 patent statutes, we have described the principles of operation of our invention, together with the apparatus which we now consider to represent the best embodiment thereof; but we desire to have it understood 50 that the apparatus shown is only illustrative, and that the invention can be carried out by other means.

We claim—

1. A carbureter including a shell containing 55 a fuel chamber and a valve chamber separated from said fuel chamber and a fuel passage communicating with the valve chamber, said structure having a carbureting chamber with an opening thereto from 60 the valve chamber, a valve located in said valve chamber and having a lateral fuel passage communicating with that in the fuel chamber, a centrally located fuel passage opening out at the end of the valve, said 65 valve also having an annular air passage

surrounding said central fuel passage, and means for operating the valve to simultaneously effect the opening of the passage from the fuel chamber and that to the carbureting chambers.

2. A carbureter including a fuel chamber and a carbureting chamber, the fuel chamber having a passage for flow of fuel therefrom, a valve having a passage to register with that from the fuel chamber, and also 75 having passages for flow of air, and means for moving the valve in one direction to simultaneously decrease and shut off the flow of fuel and air and to move it in the opposite direction to gradually increase the 80 amount of flow of air as compared with that of fuel while decreasing the amount of flow of the latter.

3. A carbureter having a fuel chamber 85 therein and a valve chamber arranged above the fuel chamber with a passage extending between said chambers, and a carbureting chamber communicating with said valve chamber, a passage for flow of fuel from the fuel chamber to the valve chamber, a valve located in the valve chamber and having a passage positioned to register with that from the fuel chamber when the valve is in an intermediate position, said valve having 90 passages for flow of air to the carbureting chamber, and means for moving the valve in opposite directions from the point in which its passage registers with that from the fuel chamber and to close the passages for flow 95 of fuel and air in its extreme movement in one direction.

4. A carbureter having a fuel chamber, a valve chamber and a carbureting chamber with a communicating passage between the fuel chamber and valve chamber, a valve 105 having a passage therethrough positioned to register with the passage from the fuel chamber and extending to said carbureting chamber, said valve also having air passages extending therethrough, a tapered valve 110 seat arranged opposite said air passages to close the same and extending around the outlet of the fuel passage from said valve, and means for operating the valve.

5. A carbureter having a fuel chamber, a 115 valve chamber and a carbureting chamber with a passage from the fuel chamber to the valve chamber, and a valve movable across the mouth of the opening from the fuel chamber to the valve chamber, said valve 120 having a fuel passage extending from its surface to a central longitudinal passage therein, the latter opening at the end of the valve, said valve also having air passages extending lengthwise therein, a valve seat 125 tapered to fit the tapered end of the valve to close passages therein, said valve seat surrounding the mouth of the opening from the central lengthwise passage in the valve, and means for operating the valve.

6. A carbureter including a shell, a cap to close said shell, a valve casing located on the cap, said cap and casing having a passage communicating with a fuel chamber in the shell, a valve located in the valve casing and movable across the mouth of the passage from the fuel chamber, said valve having an air passage extending lengthwise therethrough and terminating in an annular 40
5 passage, said valve also having a fuel passage adapted to register with the passage from the fuel chamber, the mouth of said fuel passage in the valve being located within the circle formed by said annular chamber, 45
10 a valve seat of tapered form adapted to receive the tapered end of the valve, and means for operating said valve.
7. A carbureter including a shell having a fuel chamber with a passage therefrom, a 50
15 valve casing located above said shell and having an opening to the atmosphere at one end with a tapered valve seat at the mouth of the opening from the other end of the valve casing, a valve movable in said casing 55
20 and having an annular air passage at opposite ends, and a fuel passage extending centrally therethrough, the annular passage at the inner end of the valve surrounding the outlet from the fuel passage through the 60
25 valve, and means for operating the valve.
8. A carbureter including a shell having a fuel chamber, a cap closing said chamber and having an extension screw threaded into the bottom of said fuel chamber and with 65
30 a passage through said extension, a valve casing formed integrally with the cap on the top thereof, said casing having a valve chamber communicating with the opening 70
35
- through said extension to the fuel chamber, a valve having a fuel chamber centrally therethrough with a passage to register with the passage through said extension, said valve having an annular chamber for passage of air and surrounding the outlet from said central fuel passage, and means for operating the valve. 75
9. A carbureter including a fuel chamber, a valve casing having a valve chamber with a communicating passage between said chambers, a main valve located in the valve chamber and having a central passage to communicate with that from the fuel chamber, said valve also having a passage for air, a valve extending through the main valve to control the flow of fuel therethrough, means for adjusting the position of the valve within the main valve, and means for operating the main valve. 80
10. A carbureter including a shell having a fuel chamber with a passage therethrough, a main valve having a centrally arranged fuel passage to communicate with that from the fuel chamber, a valve located in the main valve to close the outlet from the central passage therein, said main valve having a passage for flow of air, a cap loosely connected with the valve in the main valve and having longitudinal movement thereon but secured to rotate with the valve in the main valve, interengaging connections between said main valve and cap to hold the latter in predetermined positions with respect to the main valve, and means for operating the main valve. 85
